DESIGN FOR A PORTABLE BAR TRAY

Norman Bel Geddes, New York, N. Y., assignor to Creative Plastics Corp., Brooklyn, N. Y., a corporation of New York

Application September 8, 1945, Serial No. 121,949

Term of patent 14 years

(Cl. D44—10)

To all whom it may concern:

Be it known that I, Norman Bel Geddes, a citizen of the United States, residing at New York city, in the county of New York and State of New York, have invented a new, original, and ornamental Design for a Portable Bar Tray, of which the following is a specification, reference being had to the accompanying drawings, forming part thereof.

In the drawings:

Fig. 1 is a top plan view of a portable bar tray showing my new design;

Fig. 2 is a bottom plan view thereof;
Fig. 3 is a sectional view on the line 3—3 of
Fig. 1;

Fig. 4 is a sectional view on the line 4—4 of
Fig. 2; and

Fig. 5 is a front view.

I claim:

The ornamental design for a portable bar tray,
substantially as shown.
